UNITED STATES PATENT OFFICE

2,311,811

WASHING MACHINE

Horace H. Beasley, North Bergen, N. J.

Application August 7, 1941, Serial No. 405,739

7 Claims. (Cl. 248—16)

The present invention relates to appliances detachably mountable within a work tub and usually including a power unit and tool operating head, with driving connections therebetween, for work upon some tub content, as, for instance, for the washing of dishes in the tub. A device of this general character is shown in my co-pending application, Serial No. 354,639 filed August 29, 1940.

An object of the invention is the provision of means whereby, more securely and with more ease and certainty than has heretofore been attainable, the appliance may be set to the tub at any desired elevation or position therein.

Where a variable speed drive for the operating head is provided, a further object of the invention is a mounting of motor and speed controlling device such that wear and breakage of the latter due to vibration of the motor and shocks may be avoided, and certainty of operation and "set" of the speed controlling parts thus at all times assured.

A feature of the invention in a preferred embodiment thereof is the provision of a standard for the appliance adapted to bridge the interior of the tub between opposed walls thereof, and having wall-gripping legs adjustable for a preliminary setting, according to the width of the tub at any desired elevation therein, which legs are resilient, so that after the preliminary setting thereof they may be flexed toward one another for the insertion of the appliance into the tub, and thereafter be released to their spring action to exert a spring pressure against the walls of the tub, firmly to hold the appliance to the tub.

A further object of the invention in a preferred embodiment thereof is a support for the operating head and tool, such that the tool may be adjustably and rigidly held in selected position for the work to be done thereby, but may be thrown clear of the tub content to an idle position for insertion, removal, and other handling of the tub content.

Other objects and features of the invention will more fully appear upon reference to the accompanying drawings, in which:

Fig. 1 is a front view of a preferred form of apparatus embodying the present invention; a tub in which the apparatus is seated being shown in cross-section;

Fig. 2 is a view in side elevation of the apparatus shown in Fig. 1, looking from the right;

Fig. 3 is a front view of the power unit, or motor, and of the mount thereof and driving connections therefrom to the tool operating head;

Fig. 4 is a top view taken on the line 4—4 of Fig. 3;

Fig. 5 is a view in right-hand side elevation of the parts shown in Fig. 3;

Fig. 6 is an enlarged top view of the parts shown in Figs. 3 and 4, partly broken away, and showing the adjustable speed-control device in full-line driving position, and in dotted-line position for change of speed.

10 Referring to Fig. 1, 11 indicates a work tub in which a standard 11 is supported by legs 12 and 13, having feet 14 and 15, respectively, at the lower ends thereof bearing against the opposed inside faces 16 and 17 of the walls of the tub.

15 The standard 11 carries at the base thereof a tubular member or sleeve 18, and the legs 12 and 13 are offset toward each other at their upper ends, as at 19 and 20, see Fig. 1, for telescoping movement, one leg independently of the other, in the sleeve 18 at opposite ends of the latter. Set screws 21 may be loosened to permit of adjustment of the legs 12 and 13 to and from each other in the sleeve 18, and may be tightened to lock the legs 12 and 13 in the sleeve 18 in any desired adjusted position thereof.

20 The legs 12 and 13 have forwardly extending offsets 22 at their lower ends, see Fig. 2, and on these offsets are pivotally mounted the feet 14 and 15 above mentioned. The feet will turn angularly 25 on the offsets 22 and 23 to lie flush with the inside walls of the tub, as shown in Fig. 1. Any suitable means of attachment for the feet to the legs, such as for instance as shown in Figs. 1 and 2, may be provided. The feet preferably carry on their wall contacting faces strips of some non-slip material 25, see Fig. 1.

25 In mounting the standard in the tub the set screws 21 are initially loosened to permit the legs to take a position where the feet 14 and 15 are 30 slightly wider than the width of the tub at the level of the tub adapted to be engaged by said feet and the set screws are then tightened. In order to hold the feet 14 and 15 in preliminary 35 position a turn buckle 26 is utilized to connect the forward ends of the forwardly extending offsets 22 and 23 at the lower end of the legs and the legs lowered into the sink. On release of the turn buckle the legs due to their resiliency with their associated feet or shoes 14 and 15 are 40 sprung outwardly to clamp the device to the sides of the tub.

45 After the standard has been set in the tub with the set screws 21 tightened, as aforesaid, the turn-buckle is operated to flex the legs 12 and 13 slightly toward one another. This should 50

permit of a slight drop of the standard in the tub. In any such new position of the standard the feet 14 and 15 will still engage the opposite side walls of the tub. After this, the turn-buckle 26 is rotated in a direction to release the legs 25 to spring action away from one another, causing the feet 14 and 15 to be spring pressed tightly against the tub walls, with a grip thereon which will prevent any displacement of the standard when the device is in operation.

As against any force which in the operation of the device might cause the standard to be rocked angularly in the tub notwithstanding the grip of the feet 14 and 15 thereon, the following device is provided. An upper cross bar 27 of the standard has a bracket arm 28 thereon, see Fig. 2, with a U bend at the end thereof. The wings of the U are perforated in vertical alignment with each other for vertical movement therein of a rod 29. The rod 29 at one end is offset at 30 and carries thereon a lug 31 preferably shown as a thick rubber sleeve.

The rod 29, together with the lug 31, is freely movable up and down in the bracket 28, but may be secured at any desired elevation by a set screw 28'. The rod may be adjusted to bring the lug 31 into contact with the upper edge of the sink or with any ledge or other fixture. In this manner the standard 11, in addition to its support on the sink at the feet 14 and 15, is provided with means for steadyng the standard against angular displacement.

To remove the standard and parts supported thereby, it is only necessary to loosen the set screws 21 and to push the legs toward one another in the sleeve 18, thus freeing the feet 14 and 15 from the sides of the tub. The feet might also be released by turning the turn-buckle 26 to flex the legs 12 and 13 away from the tub, in which event the turn-buckle, after removal of the device, would be actuated to release the legs 12 and 13. In any event, on the removal of the device from the tub and for storage thereof, the set screws 21 are preferably released to permit the legs to be pushed toward one another as far as permitted by the ends of the sleeve 18, so that the device may be compact when not in use. After such setting is had, the set screws may be tightened to hold the legs in place to the sleeve 18.

Referring now to Figs. 3 to 6 inclusive, there is shown a casing in the form of a cabinet 50. The cross bar 27 of the standard has fixably secured to the top thereof a pair of crosswise extending bars 51. The cabinet 50 is removably secured to the bars 51, as by screws 52, passing through the bottom of the cabinet. In the right hand side of the cabinet, see Figs. 3 to 6 inclusive, is the motor, the mount therefor, and the drive from the motor to the operating head. In the left hand side of the cabinet may be any suitable tool container, (not shown), or other equipment.

An electrically driven motor 53 is shown as having on the top of the casing thereof a block 54, secured by screws 55 to the horizontal arm 56 of an L shaped bracket forming part of a motor standard which may be removably attached to the bottom of the cabinet 50. The motor standard is shown as comprising a triangular base plate 57 having blocks 58, preferably of a rubber or other shock absorbing material, secured to the upper face thereof, one at each corner as by bolts 58'. At the back of the motor base plate, and supported upon two of

the blocks 58, is a U shaped bracket consisting of a lower horizontal cross piece 59 and two parallel vertical bars 60 and 61. This bracket is set between the rear posts 58 and is supported 5 on the same by tie pieces 62 resting on the tops of the posts 58, and attached as at 63 to the vertical members 60 and 61. A brace 64 is secured at its front to the front post 58, and at its rear to the cross piece 59 of the U shaped 10 bracket.

The motor supporting bracket arm 56, together with the motor suspended therefrom, is adjustable up and down on the motor standard for speed variation, as presently more particularly to be 15 described. The vertical standard members 60 and 61, above mentioned, comprise the support on which the motor is adjustably mounted. For this purpose there is a bracket arm 65 projecting forwardly from the top of the vertical bar 60, 20 see Fig. 3. This arm 65 is fixedly secured to the bar 60, and has secured thereto, as at 66, the upper end of a coil spring 67. The lower end of this coil spring is shown as hooked into an 25 opening in the arm 56 to which as heretofore stated the motor casing is secured. The spring 67 provides a resilient and yieldable support for the motor upon the vertical bar 60. The tendency of the spring is to draw the motor upward, and the spring thus in effect counterbalances the 30 weight of the motor, so as to make hand adjustment of the motor upward and downward easy.

As shown in Figs. 3 to 6, the bar 60 has screwed or otherwise attached to the inside face thereof a pair of lugs or bearing pieces 70. Slidable vertically, and rotatable, on the bearing pieces 70 is a rod 71, having affixed thereto, somewhat centrally thereof, a vertical plate 72. This plate is set against or otherwise secured to the vertical member of the L shaped bracket 56 to which the 35 motor casing is screwed. It follows, therefore, that as the motor is adjusted upward and downward, the bracket 56, plate 72, and rod 71 move therewith.

The upright bracket member 61 has secured 40 at the upper end thereof a plate 73 shown in Fig. 3 as of U shape. The front edge of the intermediate reach of this plate 73 is graduated or notched at intervals, as indicated at 74, each such notch being indicative of some one speed 45 of drive for the motor. The plate 72, which provides the mount for the motor on the rod 71, has flexibly secured to the back thereof, as by means of rivets 75, a plate 76, shown more particularly in Fig. 4. To the back of this plate 76 is secured 50 a bracket arm, which, (see Fig. 4), extends rightward, as indicated at 77, to a point beyond the side edge of the motor supporting arm 56, and then forward as at 78 until beyond the front edge of the vertical bracket arm 61, then rightward again, as at 79, and finally forward as at 80. On the portion of 79 of this bracket arm is secured a detent 81 having a lip 82 engageable with any one of the notches 74 in the bar 73, for holding the motor at the required elevation for the 55 given speed.

As heretofore stated, the rod 71 not only supports the motor for vertical adjustment of the latter, but being itself revoluble in its bearings 70, provides for swing of the motor angularly on 60 bracket arm 60.

The detent 81 is caused to be disengaged from the graduated bracket member 73, for vertical adjustment of the motor, or engaged with such graduated bracket member, for driving of the operating head, according to the direction in 65

which the motor is swung in bearings 70. The normal or driving position of the motor is that shown by the full lines in Fig. 6, in which the detent 81 is shown as engaged with the notched bar 73.

On swing of the motor in clockwise direction, (see Fig. 6), to the dotted line position, the detent 81 is disengaged from the notched member 73 for vertical adjustment of the motor.

Carried by the motor supporting arm 56 is an arm 82' which is brought forward to the front of the motor and then extended crosswise thereof, and to the right hand end of which is attached one end of a coil spring 83. The other end of this coil spring is attached to an eye piece 84 carried by the upright 61. The tension of the spring 83 is such as to urge the motor in counterclockwise direction to bring the parts to the full line, Fig. 6, position for driving of the operating head. The flexibility of the spring 83, however, permits the motor to be turned in clockwise direction for disengagement of detent 81 from graduated bar 73. A finger piece 85 on an arm 86 connecting to the arm 80 serves as a means for swinging the motor against the action of the coil spring 83. This arm 86 is shown as protruding through an opening in the cabinet case 50, to the outside thereof, for ready accessibility.

It has been pointed out that the arm comprising the parts 71, 78, and 79, carrying the detent 81, is not rigidly attached to the motor supporting bracket plate 56, but is attached to a plate 76 resiliently connected at 75 to the bracket 56. To the arm 71 is attached another arm 87 which is bent over the top of the plate 72 and brought forward, as at 88, some distance beyond that plate, where it is again bent downward as at 89. To the part 89 of this bracket is attached one end of a coil spring 90, the other end of which is attached at 91 to the upright portion of the L shaped motor-supporting arm 56. The spring 90 tends to urge the plates 72 toward the back of the upright front of motor supporting arm 56. This resilient connection of the detent 81 to the motor supporting bracket permits the spring 83 to hold the detent in engagement with the graduated bar 73 even though the motor be subjected to considerable angular and other vibration. It is thus that the detent, or pawl and ratchet, connection for determining drive of speed is relieved of destructive shocks and strains arising from vibrations or knocks.

The driving connections to the tool operating head are as follows:

Within the motor casing is a motor-driven shaft 92 geared to a vertical shaft 93. Adjustably set to the shaft 93, as by means of a set screw 94, is a sleeve 95 carrying a friction-gear wheel 96. Carried on the upright bracket member 60 near the top thereof is an arm 97, to the forward end of which is fixedly attached a sleeve 98. Through this sleeve passes one end of a flexible driving connection 99, which extends to the operating head. Secured to this flexible driving connection at the left hand end of the sleeve 98 is a disc 100 adapted for frictional engagement with the friction wheel 96.

The nearer the wheel 96 to the axis of the disc 100 the faster the drive, and vice versa, the nearer the friction wheel 96 to the periphery of the disc 100, the slower the drive. Therefore, on upward adjustment of the motor, with the driving wheel 96, (which must move vertically therewith), a slower drive of the operating head is

effected; and vice versa, when the motor is lowered.

When the motor is swung angularly on the rod 71 against the tension of the spring 83 to release the detent 81 from the graduated bar 73, the friction wheel 96 is swung clear of the disc 100 to permit easy up or downward adjustment of the motor. On release of the motor to the action of the spring 83, driving wheel 96 is brought into driving contact with the disc as the detent 81 enters its selected notch in the bar 73.

The flexible connection 99 is shown in Fig. 3 as passing through a sleeve or cylinder, into the distal end of which a chuck 102, for any selected tool is positioned. The connection 99 may be connected to the chuck in any suitable manner.

To the underside of the right hand cross piece 51 of standard 11, at the front thereof, is secured 20 an L shaped bracket 103; and fixed to, and projecting rightward from, this bracket is the stub shaft 104. Pivoted freely on stub shaft 104 is a depending arm 105 carrying at its lower end a tool holder 106. The tool holder is a spring piece 25 bent into U shape to form a pair of jaws. Carried by the rear of these jaws, and projecting through the front one of the jaws, is a threaded stud 107. Threaded onto this stud is a hand wheel 108 adapted to be turned clockwise to 30 force the jaws toward one another and counter-clockwise to allow them to spring apart.

Each jaw 106 carries a tool gripping tongue 109. These tongues are shown as flaring outwardly from one another, so that the mandrel 110 of the 35 operating head may be laid horizontally in the pocket formed by them, or may be pushed vertically down between the same. When the mandrel is thus set vertically, the finger wheel 108 may be turned to tighten the jaws against the 40 mandrel to hold the same rigidly for any work to be done thereby over the tub content.

To move the arm 105 to working position, it is 45 swung forward on its axis on the stub shaft 103. For locking the arm in working position over the tub content, there is threaded onto the stub shaft 103 a sleeve 111. When this sleeve is turned in one direction it pinches the arm 105 to the bracket 103 to hold the arm in any angular position to which it may have been set.

50 A finger piece 112 set into the sleeve 111 and held thereto by a set screw, serves to lock and unlock the arm 105. When the operating head is not in use the arm 105 is preferably unlocked and pushed back so that the operating head and 55 tool may be clear of the tub content, for hand operation on such content. In Fig. 1 there is shown lying upon the tool carrying jaws 106 a clothes wringer 113, to which the operating head is shown as connected. This is merely illustrative of the variety of tools which may be used in 60 connection with the invention.

It will be obvious that, within the scope of the invention, the structure shown and described is susceptible of considerable modification.

65 It is claimed:

1. A standard for supporting a work unit in a 70 tub, comprising a horizontally disposed slideway member, a pair of depending legs having upper portions horizontally offset for insertion into the slideway member from opposite ends of the latter, means for adjustably securing the offset leg portions in the slideway member, and means for flexing one of the legs against the spring tension thereof to move its lower portions toward the 75 other leg, for insertion of the standard into the

tub, and for thereafter releasing the flexed leg to the spring tension thereof, for effecting a spring pressure thereof upon the side of the tub.

2. A standard for supporting a work unit in a tub, comprising a horizontally disposed slideway member, a pair of depending legs having upper portions horizontally offset for insertion into the slideway member from opposite ends of the latter, means for adjustably securing the offset leg portions in the slideway member, and a turn-buckle connecting the legs at their lower portions for flexing one of the legs against the spring tension thereof to move its lower portions toward the other leg, for insertion of the standard into the tub, and for thereafter releasing the flexed leg to the spring tension thereof, for effecting a spring pressure thereof upon the side of the tub.

3. A standard for supporting a work unit in a tub, comprising a pair of wall-gripping elements adjustable toward and from each other according to the width of the tub, for engagement each with one wall of the tub, and an adjustable arm, offset from the plane of said wall-gripping elements, for engagement with the top edge of the tub or other ledge or fixture, to prevent angular displacement of the standard in the tub.

4. A standard for supporting a work unit in a tub, comprising a pair of wall-gripping elements adjustable toward and from each other according

to the width of the tub, for engagement each with one wall of the tub, a rod adjustable in the standard and having an offset portion, and a lug on the offset portion of the rod for engagement with the top edge of the tub or other ledge or fixture to prevent angular displacement of the standard in the tub.

5. A standard for supporting a work unit in a tub, comprising a depending, pivotally mounted arm having on the lower end thereof a tool carrier, means for locking the arm in a forward tool-operating position, and for releasing the arm for movement thereof to an idle position in which it is clear of tub content.

10 6. A standard for supporting a work unit in a tub, comprising a pair of legs adjustable one with respect to the other for a spread thereof according to width of tub to be spanned thereby, means for locking the legs in relative adjustment, and means for flexing one of the legs for setting the standard to the tub, and for releasing such leg to the spring action thereof, for a spring grip of the legs upon the tub.

15 7. A standard for supporting a work unit in a tub, comprising a pair of legs adapted to span a width of tub, and means for flexing one of the legs for setting the standard to the tub, and for thereafter releasing such leg to the spring action thereof, for spring grip of the legs upon the tub.

HORACE H. BEASLEY.
